UNDERGARMENT

Morris H. Senderowitz, Allentown, Pa., assignor
to Royal Manufacturing Company, Inc., Allentown, Pa., a corporation of Delaware

Application July 12, 1949, Serial No. 104,192

1 Claim. (Cl. 2—224)

1

This invention relates to undergarments and more particularly to a garment of the type known as "shorts" or "briefs," it being one object of the invention to provide a garment of such construction that its front and crotch portions will be strongly reinforced and the fly or front opening normally held closed.

Another object of the invention is to provide a garment which is formed of fabric which is stretchable transversely and fits snugly when worn.

Another object of the invention is to provide a garment which is of simple construction and may be manufactured at low cost.

With these and other objects in view, the invention consists of a special construction and arrangement of parts illustrated in the accompanying drawing wherein:

Figure 1 is a view looking at the front of the improved garment;

Figure 2 is a vertical sectional view, taken along the line 2—2 of Figure 1;

Figure 3 is a view taken transversely through the garment, along the line 3—3 of Figure 1;

Figure 4 is a transverse sectional view, taken along the line 4—4 of Figure 1; and

Figure 5 is a fragmentary sectional view, taken along the line 5—5 of Figure 1.

This garment has a body 1 which is formed of fabric having longitudinally extending ribs so that it will be transversely expandable and will fit snugly when worn. The body has a rear section or back 2 and front sections 3 and 4 which have portions extending rearwardly to form sides for the body which are joined to side edges of the rear section by vertically extending seams 5. The lower end portion 2 of the rear section is of reduced width and to its lower edge is attached the lower end of a crotch strip 6 of double thickness which has its lower end secured thereto by a seam 7 and its upper end secured to the front sections by a seam 8. The edges of the front sections and opposite side edges of the reduced lower portion of the rear section and the crotch strip are cut to define leg openings 9 which are bordered by binding strips 10 formed of folded strips of ribbed fabric which are stretchable circumferentially of the leg openings so that they will expand when the garment is put on and have close fitting engagement with a person's legs. The fact that the binding strips are folded also causes the leg openings to be provided with smooth edges and prevents chafing by a raw edge. Meeting inner or front side portions 3' and 4' of the two front sections are overlapped to

2

form a front opening 11 and closure flap for the garment. The overlapped portions 3' and 4' have flat contacting engagement with each other so that a smooth fit is provided at the front of the garment and since the extent to which the portion 4' overlaps the portion 3' gradually increases upwardly, the free side edge of this portion or flap 4' will extend diagonally and may be readily grasped and moved away from the portion 3' to an opened position. The free edges of these overlapped portions are provided with bindings 12 formed of folded strips of fabric which extend from the seam 8 to upper ends of the said free side edges of the front sections.

15 In a garment of this character, which is formed of knitted fabric, considerable strain is applied to the front and the crotch portion, due to the fact that the garment fits tightly about the torso of the wearer. To protect the garment 20 against strains and add to the wearing qualities thereof, there has been provided reinforcing strips 13 which are formed of fabric having longitudinally extending ribs. These strips have marginal edge portions folded inwardly and sewed to 25 the front sections and the crotch strip, as shown in Figure 4. The reinforcing strips extend downwardly from the upper edge of the body portion of the garment with their upper end portions overlying the front edges of the two front sections, and upon referring to Figures 1 and 2, it 30 will be seen that the reinforcing strips or tapes diverge downwardly towards the leg openings where they are overlapped by portions of the 35 bindings 10, the reinforcements then converging downwardly and being crossed midway the length of the crotch strip, as shown at 14, and then diverge downwardly with their lower ends terminating at lower corners of the crotch strip.

Since the reinforcing strips or tapes extend 40 longitudinally of the garment with their lower portions crossed, they serve very effectively to brace the garment along the overlapped portions 3' and 4' and along the crotch strip where the greatest strain occurs, and very effectively prevent the seam 8 from being ripped loose. A waist 45 band 15 which is formed of elastic fabric extends about the top of the body where it is secured by stitching 16, and since this waist band is stretchable longitudinally, it may be expanded as the garment is put on and drawn upwardly into place, the waist band then contracting and fitting snugly about the wearer's waist to provide a comfortable fit and prevent the garment from slipping downwardly.

50 From the foregoing description of the con-

struction of my improved undergarment, the assembly thereof will be readily understood and it will be seen that I have provided a comparatively simple, inexpensive and efficient means for carrying out the various objects of the invention.

While I have particularly described the elements best adapted to perform the functions set forth, it is obvious that various changes in form, proportion and in the minor details of construction may be resorted to, without departing from the spirit or sacrificing any of the principles of the invention.

Having thus described the invention, what is claimed is:

An undergarment comprising front sections, a rear section and a crotch section, the crotch section being sewed across its front and rear edges to the lower ends of the front and rear sections, respectively, and together with the said front and rear sections defining leg openings, a waist band secured along the upper edge of the garment, the front sections having their front side edge portions overlapped between the front edge of the crotch section and the waistband and free for the major portion of their length from their lower ends to provide an opening and a closure flap, fabric reinforcing tapes sewed to the outer

faces of the front sections and the crotch section and extending vertically along the said front sections in laterally spaced relation at opposite sides of the overlapped portions thereof in downwardly diverging relation to each other between the waistband and the front end of the crotch section and then extending downwardly along the crotch section diagonally towards and in crossed relation to each other with their lower end portions diverging and terminating at the corners of the rear edge of the crotch, and fabric binding for the edges of the leg openings having portions secured in overlapping engagement with portions of the reinforcing strips along connected edges of the front sections and the crotch section.
